UNITED STATES PATENT OFFICE.

WALTER ALMON CLARK, OF CHICAGO, ILLINOIS.

HUB-ATTACHING DEVICE.

SPECIFICATION forming part of Letters Patent No. 351,095, dated October 19, 1886.

Application filed March 26, 1886. Serial No. 196,663. (No model.)

To all whom it may concern:

Be it known that I, WALTER ALMON CLARK, of Chicago, in the county of Cook and State of Illinois, have invented a new and Improved 5 Automatic Wheel-Retaining Attachment, of which the following is a full, clear, and exact description.

My invention relates to the construction of a cheap, efficient, and durable device, whereby vehicle-wheels may be secured to their axles, the apparatus being so arranged that the wheel may be removed by imparting a simple turn to the hub-cap, which, however, will be returned to its normal position by the action of 15 a spring, so that when the hub is slid upon the axle the parts will be in position to permit the automatic action of the retaining device, as will be hereinafter more fully explained.

Reference is to be had to the accompanying 20 drawings, forming a part of this specification, in which similar letters of reference indicate corresponding parts in all the figures.

Figure 1 is a central sectional view of my improved wheel-retaining attachment, certain 25 portions of the clamping-box being broken away to disclose the arrangement of the guiding-pin. Fig. 2 is a similar view of a modified construction. Fig. 3 is a detail view illustrating the construction of the hub-cap. Fig. 30 4 is a detail view illustrating the construction of the sliding clamping-box. Fig. 5 is a sectional view taken on line $x-x$ of Fig. 1. Fig. 6 is a detail sectional view taken on line $y-y$ of Fig. 3, and Fig. 7 is a detail sectional view 35 taken on line $z-z$ of Fig. 4.

In constructing such an attachment as is illustrated in the drawings above referred to, the end of the axle A is slotted, and in the slot a so formed there is arranged a double-armed 40 spring catch or plate, B, that is held to position by a pin, b , the catch C at the end of the spring arms c being arranged beyond the extreme end of the axle, and the outer faces of said catches being inclined or beveled, as 45 clearly shown in the drawings. In connection with the axle, arranged as described, and a wheel-hub, D, recessed in the usual manner, I employ a hub-cap, E, the inwardly-projecting flange e of which fits loosely in the recess of the hub, said cap being formed with slots f , arranged upon opposite sides of the flange and at right angles to the axis of the cap.

The cap E is provided with an inwardly-projecting pin, h , which rides in a longitudinal groove, k , formed in a sliding clamping-sleeve, F, that is loosely fitted within the cap E, and this sleeve F is also formed with two diagonal slots, g , as best shown in Figs. 4 and 7, the several parts being held together and being secured to the hub D by means of a bolt 60 or screw, H, which passes through the slots f of the cap E and the slots g of the sleeve F. A spring, i , is fixed to the inner face of the cap E and also to the bolt or screw H.

It will be noticed that there is an annular 65 shoulder, n , formed in the hub D, just inside of the flange e , and when the hub is forced to the position shown in Fig. 1 the catches C C will spring out and will be brought into engagement with this shoulder, thus preventing 70 the withdrawal of the hub; but if it is desired to remove the wheel from the axle, the cap E is firmly grasped and slightly turned to the right, the wheel being held stationary at this time. Now, this turning of the cap E will 75 cause the sleeve F to advance, and as the sleeve advances it will strike the flaring beveled faces of the catch-teeth C and move said teeth toward each other against the tension of their springs c , the motion being continued 80 until the teeth are freed from engagement with the shoulders n , after which the hub and the wheel which it carries may be slid off the axle. In moving the cap E to the right the spring i is necessarily subjected to a high tor- 85 sional strain, and when the cap is released it will be returned to its normal position. In certain cases I prefer to employ a circular wear plate or washer, O, arranged as clearly shown in Fig. 2, thus relieving the shoulder 90 n from wear.

Now, although I have described and illustrated a specific arrangement of parts, I desire it to be distinctly understood that I do not limit myself to the precise construction 95 shown, as many and various modifications of such construction could be made without departing from the spirit of my invention.

The facility and ease with which the wheels may be disconnected and removed from their 100 axles for the purpose of lubricating the axles, or for any other purpose, will be readily appreciated; and it will also be appreciated that with the construction shown there will be lit-

tle or no liability of the axles being injured by grit, as the cap E effectually closes the outer opening of the hub; and it will still further be appreciated that as the ordinary form 5 of dirty, greasy nut is dispensed with, the operator will not be liable to soil his hands or clothes in disconnecting the wheel from its axle.

Having thus fully described my invention, to what I claim as new, and desire to secure by Letters Patent, is—

1. The combination, with a slotted axle and a spring-catch held therein, of a hub-cap provided with a movable sleeve, and means for 15 moving said sleeve longitudinally, substantially as described.

2. The combination, with an axle, of a plate secured within a slot formed at the end of the axle, and provided with spring-arms carrying 20 catches formed with inclined or beveled faces, a hub-cap formed with transverse slots, and an inwardly-extending pin, a clamping-sleeve formed with diagonal slots, and a longitudi-

nal slot in which the inwardly-projecting pin of the cap fits, and a bolt or screw passing 25 through the transverse slots of the cap and the diagonal slots of the clamping-sleeve, substantially as described.

3. The combination, with an axle, of a plate secured within a slot formed in the end of the 30 axle, and provided with spring-arms carrying catches formed with inclined or beveled faces, a hub-cap formed with transverse slots, and an inwardly-extending pin, a clamping-sleeve 35 formed with diagonal slots, and a longitudinal slot in which the inwardly-projecting pin of the cap fits, a bolt or screw passing through the transverse slots of the cap and the diagonal slots of the sleeve, and a spring secured to the cap, and the retaining bolt or screw, substantially as described.

WALTER ALMON CLARK.
